UNITED STATES PATENT OFFICE.

BROR MAX SCHAUMAN, OF ATLANTIC HIGHLANDS, NEW JERSEY, ASSIGNOR OF ONE-FIFTH TO GRANDIN V. JOHNSON, ONE-FIFTH TO OTTO GAUTSCHY, AND ONE-FIFTH TO HARRY N. JOHNSON, ALL OF HIGHLANDS, NEW JERSEY, ONE-FIFTH TO WILLIAM KOCH, OF LONG BRANCH, NEW JERSEY, AND ONE-FIFTH TO BROR MAX SCHAUMAN, OF ATLANTIC HIGHLANDS, NEW JERSEY, AN ASSOCIATION.

HEATING FURNACE.

Application filed May 28, 1921, Serial No. 473,505. Renewed February 5, 1925.

To all whom it may concern:

Be it known that I, BROR MAX SCHAUMAN, a citizen of the United States, residing at Atlantic Highlands, in the county of Monmouth and State of New Jersey, have invented certain new and useful Improvements in Heating Furnaces, of which the following is a specification.

This invention relates more particularly to heating furnaces of the single register type, as will be clear from the following specification.

The objects of the invention are to provide for the accumulation and storage of the heat and hence to prevent waste of heat, and at the same time, to provide in effect a reservoir from which the heat may be drawn as required.

My invention aims to accomplish these desired results in a simple, practical and relatively inexpensive manner.

In the accompanying drawings I have illustrated a simple and preferred embodiment of the invention, but would have it understood that the structure may be modified without in any way departing from the true spirit and scope of the invention as hereinafter defined and claimed.

Figure 1 is a vertical sectional view of the invention embodied in a single register type of furnace.

Figure 2 is a horizontal sectional view of the same, as taken on substantially the plane of line 2—2 of Figure 1.

Figures 3, 4 and 5 are similar views, taken on substantially the planes of lines 3—3, 4—4 and 5—5 of Figure 1, all of these sectional views being drawn on somewhat smaller scales than the scale of Figure 1.

Figure 6 is a broken, vertical sectional view taken on substantially the plane of line 6—6 of Figure 4.

Figures 7 and 8 are plan and edge views respectively of the auxiliary air ring or carbureter.

The furnace illustrated is of the coal-burning type and has a closed ash pit 10, fire pot 11 and combustion chamber 12.

Grouped about the fire pot and combustion chamber are a series of tubular columns connected at top and bottom by the head piece 13 and the base 14. A special feature of these parts is that they are made of fire clay or some other suitable and efficient heat storing and exchanging fire resisting medium.

These tubular columns and the head and base members provide a circuitous smoke conduit, one end of which is connected by suitable piping 15 (Figure 1) with the combustion chamber. The smoke conduit in this particular illustration is constituted as follows: from the smoke inlet 15 through a curved passage 16 in the head block to the vertical passage in the first column 17 and from the base of this column through a passage 18 in the base to an upright pipe 19 which extends through the wall of the combustion chamber, and has a re-entrant portion 20 located within the combustion chamber. The upper end of the re-entrant portion 20 extends out through the wall of the combustion chamber to a passage 21 (Figure 3) in the head block which is in communication with the passage in the second column 24, and the base block connects this by a loop passage 25 with the lower end of the third tubular column 26.

The upper end of this third column connects with a loop passage 27 in the head block opening into the top of the fourth column 28. The foot of this column is connected by a loop passage 29 in the base (Figures 4 and 5) with piping 30 having a re-entrant portion 31 disposed within the combustion chamber and connected at its upper end with an elbow passage 32 in the head block opening into the top of the fifth column 33. The lower end of this column is connected by a loop passage 34 with piping 35 having a re-entrant portion 36 disposed in the combustion chamber and connected at the top with a passage 37 in the head which opens into the top of the column 38. The bottom of this column is connected by a loop passage 39 in the base with the

lower end of column 40 whose upper end is connected by a loop passage 41 in the head with the top of column 42 and the latter is connected at its lower end by loop passage 43 in the base, with the final column 44 which opens at its upper end into a smoke duct or flue 45 leading to a suitable stack.

The head and base elements may be made in one or a number of parts as circumstances require. In the construction illustrated, the base is made in three segmental parts shaped to provide a recess between them for the ash pit (Figure 5), and the head is made in three segmental parts (Figures 2 and 3) shaped to provide a recess for the combustion chamber and recessed at the outer edges at one or more points, as indicated at 46, to allow for circulation of the air being heated.

The parts thus far described are surrounded and encased within a suitable housing, such as I have indicated at 47, and within the upper portion of this housing there is provided a funnel shaped collector 48 having a neck 49 providing a hot air outlet and forming between it and the surrounding wall 50, an annular inlet 51 for the air which is to be heated.

The fresh air taken in through the inlet 51 passes downward and after circulating about the heat retaining or accumulating columns, head and base members and about the fire pot and combustion chamber, rises and passes out through the outlet 49 into the room to be heated. The relatively long circuitous smoke passage serves to extract substantially all the heat from the smoke and the re-entrant portions of such conduit accomplish a further extraction of heat from the fuel. I find, in fact, that the construction disclosed operates in effect as an accumulator, holding the extracted heat in storage ready to be used whenever necessary.

It is, of course, understood that the outlet 49 which, for convenience of illustration, is shown as terminating at the furnace top, may be extended in practice in the manner usual in ordinary hot-air furnaces to deliver the heated air at distant points wherever desired; or, what amounts to the same thing, the inlet pipe 50 may be extended to the points which it is desired to heat. In either case the draught which would be caused by the rush of the cold air to the furnace is avoided. In the first case, by delivering the warm air at a distance, any air which is drawn toward the furnace is warm and causes no discomfort; and in the second case a draught is avoided by confining within a pipe the cold air which is drawn toward the furnace. It is apparent also that special cases may arise in which it is desirable that the warm air is delivered at a distance and also that the cold air shall be drawn from a distance. In other words,

the warm air generated by the furnace may be delivered to any point and the cold air may be drawn from any suitable point, as specific conditions in any given case may dictate.

To promote complete combustion of fuel, I have shown in Figures 1, 7 and 8 an auxiliary air supply ring 52 resting on an annular shoulder 53 provided at the junction of the fire pot with the wall of the combustion chamber and having a neck 54 extending out to the exterior of the furnace and there provided with a regulatable damper 55. The top of this air supply ring is inclined downwardly so as to shed fuel and ashes and this downward inclination also tends to cause the inducted air to be sprayed downwardly on the fuel and hence to combine more readily with the gases of combustion. In starting the fire and in fact at other times, it may be desirable to send the smoke directly to the stack and for this purpose I have illustrated at 56 a smoke outlet conduit open to the top of the combustion chamber as shown in Figure 1, and extending directly to the rear to the outlet duct 45, as shown in Figure 2. Suitable valves or dampers 57 and 58 are provided in this duct, said dampers being controlled by handle rods 59, 60 respectively.

A further possibility of control is obtained by providing the smoke outlet with a branch passage 61 extending laterally into communication with the top of the column 38 (Figure 2), and provided with a damper 62 controlled by a handle rod 63.

When the smoke and flame are to be sent directly to the stack, both dampers 57 and 58 are opened so as to pass the smoke from the combustion chamber direct to the stack. This in effect by-passes or short-circuits the circuitous heat exchanging conduit and on account of the direct path thus provided, accelerates combustion, an advantage in the starting or quickening of the fire.

By opening the dampers 57 and 62 and closing the damper 58, a portion only of the heat exchanging conduit will be utilized, that portion which includes the heating columns 38, 40, 42 and 43. This elimination of the first part of the heating conduit facilitates burning of the fire without sacrificing the entire heat exchanging effect of the circuitous smoke conduit.

Another special feature of my invention is the provision of the furnace air inlet with downwardly extending flues, such as shown at 65 in Figure 6, which carry the fresh air down close to the surface of the liquid in the water pans 66 which are suitably supported in the base portion of the furnace. This causes dust carried by the incoming air to be deposited in the water and the water as therefore utilized as a purifying agent as well as a humidifying element. The air

is thus automatically cleansed and properly moistened as soon as it enters the heating chamber.

What I claim is:

5. 1. In a heating furnace, a combustion chamber, a heat exchanging body having a circuitous smoke passage therein connected with the combustion chamber, means for passing the medium to be heated about said heat exchanging body, and connections between different sections of the body re-entrant into the combustion chamber.

10. 2. In a heating furnace, a combustion chamber, a heat exchanging body having a circuitous smoke passage therein connected with the combustion chamber, means for passing the medium to be heated about said heat exchanging body, and means for cutting sections of the body passage out of circuit.

15. 3. In a heating furnace, a combustion chamber, a circuitous smoke conduit extending from said combustion chamber made up in part of a heat refractory body and having re-entrant portions extending back into the combustion chamber, and a casing enclosing the heat exchanging body of the smoke conduit and provided with means for circulating the air to be heated about the body and combustion chamber.

20. 4. In a heating furnace, a combustion chamber, a circuitous smoke conduit extending from said combustion chamber made up in part of a heat exchanging body and having re-entrant portions extending back into the combustion chamber, a casing enclosing the heat exchanging body of the smoke conduit and provided with means for circulating the air to be heated about the body, and combustion chamber and adjustable means for by-passing sections of the heat exchanging body.

25. 5. In a heating furnace, a combustion chamber, a circuitous smoke conduit extending from said combustion chamber made up in part of a heat exchanging body and having re-entrant portions extending back into the combustion chamber, a casing enclosing the heat exchanging body of the smoke conduit and provided with means for circulating the air to be heated about the body and combustion chamber, and adjustable means for by-passing sections of the heat exchanging body, including a smoke outlet from the combustion chamber having a direct passage for connection with a stack and a branch passage for connection with an intermediate section of the heat exchanging body, and dampers in said outlet for controlling flow through the same.

30. 6. In a heating furnace, a combustion chamber, a circuitous smoke conduit extending from said combustion chamber made up in part of a heat exchanging body and having re-entrant portions extending back into

the combustion chamber, a casing enclosing the heat exchanging body of the smoke conduit and provided with means for circulating the air to be heated about the body and combustion chamber, an auxiliary air inlet 70 in the combustion chamber below the re-entrant portions of the smoke conduit, and means for controlling admission of combustion supporting air thereto.

7. In a furnace of the character described, a combustion chamber, upright tubular columns about the same, each column having a vertical passage therethrough, a base on which said columns are supported and a head resting on said columns, said columns, base and head being constructed of heat exchanging fire clay and the base and head having loop passages therein connecting the passages in the tubular columns and forming with such passages a circuitous smoke passage, said smoke passage being connected with the combustion chamber and means for circulating the air to be heated about said heat exchanging columns, head and base.

8. In a furnace of the character described, a combustion chamber, upright tubular columns about the same, each column having a vertical passage therethrough, a base on which said columns are supported and a head resting on said columns, said columns, base and head being constructed of heat exchanging fire clay and the base and head having loop passages therein connecting the passages in the tubular columns and forming with such passages a circuitous smoke passage, said smoke passage being connected with the combustion chamber and means for circulating the air to be heated about said heat exchanging columns, head and base, the smoke passage described having intermediate re-entrant portions disposed within the combustion chamber.

9. In a heating furnace having an outlet, a combustion chamber, a heat exchanging body, a passage from said chamber through the body to said outlet, a second passage from said chamber direct to said outlet, and means for cutting out of the heating circuit the passage through the body.

10. In a heating furnace having an outlet, a combustion chamber, a heat exchanging body, a passage from said chamber through the body to said outlet, a second passage from said chamber direct to said outlet, and means for cutting out of the heating circuit a portion of the passage through the body, the products from the combustion chamber being diverted from said cut-out portion to said direct passage.

11. In a heating furnace having an outlet, a combustion chamber, a heat exchanging body, a passage from said chamber through the body to said outlet, a second passage from said chamber direct to said outlet, means for cutting out of the heating circuit

the passage through the body, and means for cutting out of the heating circuit a portion of the passage through the body.

12. In a heating furnace having an outlet, a combustion chamber, a heat exchanging body, a passage from said chamber through the body to said outlet, a by-pass having

communication with the beginning, end, and an intermediate portion of the passage, and dampers in said by-pass at said communicating points for controlling the heat circuit through said passage and said by-pass.

In testimony whereof I affix my signature.

BROR MAX SCHAUER.
